UNITED STATES PATENT OFFICE.

JOHN SHANKEY, OF ST. LOUIS, MISSOURI.

ADJUSTABLE WINDOW-SCREEN.

SPECIFICATION forming part of Letters Patent No. 538,540, dated April 30, 1895.

Application filed November 8, 1892. Serial No. 451,373. (No model.)

To all whom it may concern:

Be it known that I, JOHN SHANKEY, of the city of St. Louis, in the State of Missouri, have invented a certain new and useful Improvement in Adjustable Window-Screens, of which the following is a full, clear, and exact description, reference being had to the accompanying drawings, forming part of this specification.

10 My improvement relates to that class of invention which has for its object the production of a window screen readily adjusted to windows of varied widths and which with a few sizes meet all requirements necessary to 15 make a complete screen, and which will occupy a space equal to the lower window sash, when the screen is down and when up will occupy a space equal to the space occupied by the upper sash, and will not at any time 20 interfere with the raising and lowering of either of the sashes.

Referring to the drawings, Figure I is a front elevation of a window-screen, from which the lower-facing cross-bar is broken away to more clearly illustrate the construction beneath. Fig. II is a perspective view of the screen, from which one of the adjustable side wings is shown detached. Fig. III is an outside view of the screen in position in a window-frame, the screen being shown in lower closed position. Fig. IV is a similar view showing the screen in raised position. Fig. V is a horizontal transverse section taken above the top of the screen on line V V, Fig. 35 III. Fig. VI is a horizontal transverse section taken through the screen on line VI VI, Fig. III.

Referring to the drawings 1 is a sheet of wire gauze or other screen-material, secured 40 to an outer frame consisting of a bottom strip 2, a top strip 3, and side strips 4 and 5. Secured to the bottom and top strips are two inner strips 2^a 3^a each formed with an internal groove 8, providing inwardly projecting 45 flanges 8^a, and with inner end tongues 8^b and outer end tongues 8^c providing slots 10 between them, and slots 10^a between them and the adjacent strip.

6 represents adjustable side wings having 50 at each end slides 7, which fit and work in internal grooves 8. 9 are bosses or guides on the sides of the adjustable side wings which

fit and work in slots 10. 6^a are the tongues of the wings fitting in the end slots 10^a. In the body of the adjustable side wings 6, near 55 their ends are elongated slots 11 through which pass thumb-screws 12 that work in threaded openings 13 in the stiles 4 and 5. The thumb screws 12 have enlarged heads 14 and shoulders 15, such shoulders bearing when 60 tightened, against a plate 16 that covers the elongated openings 11 at the side of the thumb screws 12, and thus prevent ingress of insects through the opening. When the parts are connected, the screws 12 control the movement of 65 the adjustable side wings, and when tightened firmly secure the side wings to the stiles of the screen in any set position, to fit a window frame.

The screen being placed within the window 70 frame 17, the inner face of the adjustable side wings fit between the ordinary guide strip 18 and a strip 19 secured to and extending the entire length of the window frame, the two strips forming a groove 20 in which the 75 screen may be raised or lowered independent of and out of contact with either sash of the window.

The operation of the screen is as follows:— The screen being placed within the window 80 frame, the adjustable side wings are moved outward until their outer edges bear within the groove 20, against the face of the window frame, and the screws 12 are then tightened until the shoulders 15 of the screws coming 85 in contact with the plate 16 clamp or draw the parts together, securing the side wings in a fixed position between the sides of the window frame, and the screen may be moved up and down in the grooves 20 at will, without 90 interfering with the window sashes, or without further adjustment or attention until it may be desired to remove it from the window.

I claim as my invention—

A window-screen comprising the outer 95 frame consisting of the bottom strip 2, the top strip 3, and side strips 4, 5, the sheet secured to the frame, the inner top and bottom strips 2^a, 3^a, each formed with an internal groove 8 providing inwardly projecting 100 flanges 8^a, and with inner end tongues 8^b and outer end tongues 8^c providing slots 10 between them and slots 10^a between them and the adjacent strip, and the adjustable side

wings 6 having upper and lower end slides 7 fitting the internal grooves, the upper and lower end tongues 6^a fitting the slots between the tongues and the adjacent strips, the upper and lower guides 9 fitting between the tongues, and the upper and lower elongated slots 11, the cover plates 16 for the elongated

slots, and the securing thumb screws 12; substantially as described.

JOHN SHANKEY.

In presence of—
ALBERT M. EBERSOLE,
ED. S. KNIGHT.
